UNITED STATES PATENT OFFICE.

ARTHUR KOCHENTHAL, ARTHUR W. MOCK, AND ALEXANDER JACOBI, OF ROCHESTER,
NEW YORK.

CIGARETTE OR CIGAR BOX.

No. 911,248.

Specification of Letters Patent.

Patented Feb. 2, 1909.

Application filed September 30, 1907. Serial No. 395,121.

To all whom it may concern:

Be it known that we, ARTHUR KOCHENTHAL, ARTHUR W. MOCK, and ALEXANDER JACOBI, citizens of the United States, and 5 residents of Rochester, in the county of Monroe and State of New York, have invented a new and Improved Cigarette or Cigar Box, of which the following is a specification.

10 This invention relates to that class of boxes in which the cigars or cigarettes are usually sold to the retail trade and pertains more especially to the cover of such a box, in which there is provided a suitable means 15 for carrying a sufficient number of matches to supply the needs of the user in lighting the cigarettes or cigars contained in the box.

The purpose of the present invention is to provide an efficient and economically constructed match carrying cigar or cigarette box and one in which the matches will be properly held in place regardless of whether the box is removed from the pocket of the user right or wrong side up.

25 Another object is to provide a box of such a character that the matches may be readily removed therefrom upon a proper manipulation of the connecting parts.

Another feature of the invention is to provide, in connection with such a box, a suitable surface for lighting the matches on and also a means for protecting the matches from contacting with the cigars, such means affording also an attachment for withdrawing the match carrier to a position where the matches may be readily removed therefrom. It is also preferable that when the match carrier is forced into place to restore all the parts to their normal positions, the 40 accidental removal of the matches will be prevented and the heads thereof protected, when it is desired to use a protecting flap, from contacting with the cigars or cigarettes in the box.

45 With these objects in view, our invention comprises a sheet of suitable material properly scored up along, preferably, six lines. Starting with the edge towards the hinged side of the cover, there is bent backwardly 50 along the line of the first score an attaching flap, by means of which the match carrying attachment is secured to the inside of the cover by any suitable cement. From this fold the finished carrier extends parallel with 55 the top of the box cover and it is bent out-

wardly at right angles thereto at the next or second score line and then again at the third score line it is bent upwardly parallel with the plane of the top of the cover but a slight distance therefrom, then at the next 60 or fourth score line it is bent backwardly so as to contact with the top of the cover, then at the fifth score line upwardly parallel or in contact with the top of the cover, and then from the sixth score line the sheet is preferably curved to form a flap, when it is desired to use the flap, adapted to extend over the heads of the matches. The two first mentioned portions of such sheet extending at right angles with the plane of the top of 70 the cover have holes therethrough to receive the matches. By means of either the protecting flap, when used, or a suitable engaging member, in place thereof, the upper edge of the free end of the match carrier may be 75 withdrawn from the box cover sufficiently to permit of the removal of the matches which are held against such removal by either the front edge of the box or by the flap of the carrier lying adjacent thereto 80 when the carrier is forced back in position within the box cover. The front or exposed face of that portion of the carrier lying in front of the matches may be coated to form a suitable igniting surface.

85 The accompanying drawings illustrating a cigar or cigarette box made in accordance with our invention are as follows, viz.: Figure 1 shows in perspective one of such boxes opened. Fig. 2 shows the lid or cover 90 C of the box in vertical section. Fig. 3 shows the match carrying plate or sheet removed from the cover. Fig. 4, shows the blank from which the match carrying sheet is formed. Fig. 5 is a view similar to Fig. 2 95 of a modification, as will be explained. Fig. 6 shows in vertical sectional view the cover 100 C and a portion of the box B and with the match carrier swung outwardly for the purpose of removing a match therefrom, one of such matches being shown in dotted lines as partially removed. Fig. 7 is a modification to be explained.

Similar letters refer to similar parts throughout the several figures of drawing.

105 Referring to the drawings,—B is the body of the box and C the cover and within the body of the box B are seen cigarettes or cigars b. The cover C is hinged or flexibly connected, in the usual way, to the body B.

We have found it desirable to adapt the match carrier portion of our box to swing with its lower edge in the corner formed by the top of the cover and the back or rear side member thereof and while it is not necessary, we prefer that the match carrier have an attaching flap, by means of which it may be flexibly secured in such corner between the top of the cover and the rear side member thereof. Such attaching flap is seen at e in the several figures of drawing, and it may be suitably secured to the top of the cover by means of cement or otherwise, as desired, preferably by cement.

Our match carrier is formed integrally from a sheet of suitable material, such as thin, tough pasteboard or heavy paper in the following way, viz.: A sheet of paper or cardboard, as seen at E in Fig. 4, is scored 10 along the lines i , i^1 , i^2 , i^3 , i^4 and i^5 , the dotted ones of such lines indicating that the scoring is done on the reverse or rear side of the sheet. The portion of the sheet e below the score line i is folded backward to form the 15 attaching flap. The portions of the sheet e^2 between the score lines i^1 and i^2 and i^3 and i^4 are bent outwardly at right angles with the plane of the sheet, while the portion e^3 between the score lines i^2 and i^3 is arranged 20 to lie parallel with the main portion of the sheet and parallel also with the top of the box cover. Through the portions e^2 of the sheet there are formed holes o of suitable size to receive the matches when the carrier 25 is formed up, as indicated in Figs. 1, 2, 3, 5 and 6. The portion of the sheet E between the score lines i^4 and i^5 is arranged to lie parallel with and normally against the inside of the body of the cover C . Above the 30 score line i^5 the portion e^3 is bent to the conformation substantially as indicated in Figs. 2, 3 and 6, such curved portion e^3 being, on account of the score line i^5 , flexibly connected to the main portion of the sheet E 35 and the conformation and proportion of the parts of this flap member e^3 are such that when the match carrier is forced to the position indicated in Figs. 1 and 2, the curved part of this flap e^3 bears against the inner 40 surface of the front side member c of the cover C to firmly hold the parts in the position indicated in Figs. 1 and 2, in which position the flap e^3 serves to protect the heads of the matches as well as to hold the 45 parts in such closed position. Before the parts are forced to the position indicated in Figs. 1 and 2, the matches m are inserted through the holes o in the portions e^2 of the carrier plate E . In place of the protecting 50 flap e^3 we may make use of an engaging member e^4 such as seen in Fig. 5, the action of which when holding the parts in their closed position, is the same as that already described in relation to the flap e^3 , except 55 that the member e^4 does not extend down-

wardly over and protect the heads of the matches.

We desire to call attention to the following features:—The carrier is adapted to articulate at its lower end within the corner 70 formed by the top and rear side members of the cover and while not necessary, still, it is preferable that the carrier be secured to the cover by means of an attaching flap flexibly united to the main body of the cover. The 75 flap e^3 or the engaging member e^4 , either one, operates, when used, to retain the parts in their closed positions and also serves as an engaging member for the withdrawal of the carrier sufficiently to remove the matches 80 therefrom. The flap e^3 or the engaging member e^4 , by means of their flexible connection with the body E of the carrier, form a wedging or locking member to hold the carrier in its closed position. The matches 85 are readily removable from the box or the carrier therein upon the withdrawal of the outer end of the carrier in the way described, still, the matches are held against accidental removal by the front side c of the cover C 90 and that too regardless of what position the box B may be in, when opened, whether right or wrong side up, and also whether held horizontally, vertically or obliquely.

In Fig. 6 one of the matches is shown in 95 dotted line as partially removed. The face of the section e^1 of the carrier may be coated to form a suitable igniting surface, as indicated in Figs. 1 and 3, upon which the matches may be lighted.

The use and operation of our box is believed to be sufficiently obvious from the foregoing explanation to call for no further description herein.

By forming the carrier as seen in Fig. 7 at 105 E^1 , where the front flap is shown extended down around and to the lower edge of the carrier at e^7 and with the flap e^6 extending forwardly instead of being bent up on the rear side, the carrier is adapted to independent use and it may also be inserted in the 110 box.

We claim—

1. A box for cigars or cigarettes having a match carrier adapted to articulate with the 115 cover of such box and at the corner between the top and a side of such cover, such carrier permitting the ready insertion and removal of matches therefrom when swung outwardly so that the matches may pass beyond the outer edge of the side of such cover, such carrier having flexibly connected at its free end a locking member adapted to engage on the inside of one side of the box cover to hold such carrier in its closed position.

2. A box for cigars or cigarettes having a match carrier adapted to articulate with the cover of such box and at the corner between the top and a side of such cover, such carrier permitting the ready insertion and re- 130

removal of matches therefrom when swung outwardly so that the matches may pass beyond the outer edge of the side of such cover, such carrier having flexibly connected at its 5 free end a locking member adapted to engage the inside of one side of the box cover to hold such carrier in its closed position, and such locking member adapted also to be engaged by the hand of the user to withdraw 10 the carrier outwardly.

3. A box for cigars or cigarettes having a match carrier adapted to articulate with the cover of such box and at the corner between the top and a side of such cover, such carrier 15 permitting the ready insertion and removal of matches therefrom when swung outwardly so that the matches may pass beyond the outer edge of the side of such cover, such carrier having flexibly connected at its free 20 end a locking member adapted to engage the inside of one side of the box cover to hold such carrier in its closed position, such locking member comprising a flap adapted to protect the heads of the matches from contacting with the contents of the box.

4. A box for cigars or cigarettes having a match carrier formed from a single sheet of suitable material, the main portion of which is adapted to lie in two substantially parallel 30 but separated planes, the connecting members between such parallel portions having perforations to receive the matches and hold them in a plane parallel to the main body portion of the carrier, such carrier having at

one edge a portion thereof adapted to bend 35 from the normal plane of the sheet along a substantially straight line and such bent portion secured to the cover of the box near the inner corner.

5. A box for cigars or cigarettes having a 40 match carrier formed from a single sheet of suitable material, the main portion of which is adapted to lie in two substantially parallel but separated planes, the connecting members between such parallel portions having 45 perforations to receive the matches and hold them in a plane parallel to the main body portion of the carrier, such carrier having at one edge a portion thereof adapted to bend from the normal plane of the sheet along a sub- 50 stantially straight line and such bent portion secured to the cover of the box near the inner corner and such carrier also having at the opposite edge a second flexibly connected portion adapted to fold over the ends of the 55 matches, to engage with frictional engagement on the inside against the outer side of the box cover and also adapted to be engaged by the hand of the user to swing the 60 cover outwardly to permit the removal of the matches.

ARTHUR KOCHENTHAL.
